Des. 68,665

UNITED STATES PATENT OFFICE.

FRED F. SOWL, OF DULUTH, MINNESOTA.

DESIGN FOR A BOOKLET COVER.

Application filed June 19, 1925. Serial No. 13,827. Term of patent 7 years.

To all whom it may concern:

Be it known that I, FRED F. SOWL, a booklet cover, showing my new design. citizen of the United States, residing at Duluth, in the county of St. Louis and State of Minnesota, have invented a new, original, and ornamental Design for Booklet Covers, reference being had to the accompanying drawing, forming part thereof.

The figure is a perspective view of a booklet cover, showing my new design.

I claim:

The ornamental design for a booklet cover, as shown.

FRED F. SOWL.
